UNITED STATES PATENT OFFICE

118,567

DESIGN FOR AN INKWELL OR THE LIKE

Archie D. Robinson, Westfield, Mass.

Application August 21, 1939, Serial No. 86,822

Term of patent 7 years

To all whom it may concern:

Be it known that I, Archie D. Robinson, a citizen of the United States, residing at Westfield, in the county of Hampden and State of Massachusetts, have invented a new, original, and ornamental Design for an Inkwell or the like, of which the following is a specification, reference being had to the accompanying drawing, forming part thereof.

Fig. 1 is a perspective view of an inkwell showing my new design looking at the front side thereof; and

Fig. 2 is a perspective view of the same looking at the rear side thereof.

I claim:

The ornamental design for an inkwell or the like, as shown.

ARCHIE D. ROBINSON.
